Emile C. Guedon,
BY *J. R. Goldsborough*,
ATTORNEY.

UNITED STATES PATENT OFFICE

2,086,415

MAGNETIC PICK-UP

Emile Charles Guedon, Audubon, N. J., assignor
to Radio Corporation of America, a corporation
of Delaware

Application December 23, 1933, Serial No. 703,742

8 Claims. (Cl. 179—100.41)

My invention relates to electro-magnetic translating devices, and more particularly to electrical pick-ups.

The main object of my invention is to provide an electrical pick-up which can be produced cheaply and which, at the same time, shall have satisfactory electrical and mechanical characteristics.

A further object of my invention is to provide a pick-up unit that shall be easy to assemble in quantity production.

A further object of my invention is to provide an electrical pick-up having minimum number of parts.

Still further object of my invention is to provide an improved pick-up unit and supporting arm assembly.

In practicing my invention I employ a unitary pole piece construction in a pick-up of the type having a fixed coil threaded by magnetic flux which varies in accordance with the movement of an armature. In this unitary construction, the two pole pieces are integral parts of a member of magnetic material, and are separated by an air gap which is not adjustable. A portion of this member forms part of the support for the armature to hold it in proper relation to the air gap.

A pick-up arm is provided which is shaped at one end to form a casing for the pick-up unit, this casing, together with a bottom plate, serving both to enclose the pick-up unit and to hold its parts in assembled relationship.

Other objects, features and advantages of my invention will appear from the following description taken in connection with the accompanying drawing in which,

Figure 1 is a view, taken in longitudinal section, of an electrical pick-up constructed in accordance with my invention;

Fig. 2 is a view taken on the line 2—2 of Fig. 1;
Fig. 3 is a view taken on the line 3—3 of Fig. 1;

Fig. 4 is a perspective view of a unitary pole piece member comprising one portion of the structure shown in Fig. 1;

Fig. 5 is a bottom view of the pole piece unit shown in Fig. 4;

Fig. 6 is a perspective view of a portion of the structure shown in Fig. 1; and

Fig. 7 is a view taken on the line 7—7 of Fig. 1.

Referring to Figs. 1, 2 and 3, the electrical pick-up comprises a pick-up arm 1 pivotally mounted at one end and shaped at the other end to form a casing 3. The pick-up unit proper

5
ally at 5, and a permanent magnet 7. The magnet 7 is clamped between the pick-up arm casting 3 and the assembled unit 5 as shown in Fig. 3.

The assembled unit 5 comprises an armature 9 having an armature pivot shaft 11 which extends on opposite sides of the armature. The upper end of the armature 9 is flattened and positioned between pole pieces 13 and 15. The lower end of the armature 9 is hollow to permit the insertion of a stylus 17 which may be clamped in position by means of a set-screw 19 extending into a hollow portion of the pivot shaft 11.

In accordance with my invention, the pole pieces 13 and 15 are part of a unitary construction, the design of which will be more clearly 15 understood by referring to Figs. 4 and 5. This structure consists of a U-shaped member 21 of magnetic material. The upper part of the member 21 consists of two pole piece portions 13 and 15 which are separated by an air gap 23, the adjacent ends of the pole piece portions being of reduced cross-sectional area as indicated on the drawing.

extending portion 39 having a plurality of tapped holes 41 therein for fastening bottom plate 32 to the pick-up casing 3. In the middle of this portion there is a rectangular opening 43 which is provided to house a rectangular block of inert damping material such as the composition commercially known as Viscoloid, or the like if desired. As the use of such damping material is no part of my present invention, it has not been shown in the drawing. It is to be understood, however, that the block is operatively connected to the pivot shaft 11 in a commercial embodiment of my invention.

At the other end of the plate 32, there are two upwardly extending portions 45 and 47, the portion 45 being provided to act as a support for a terminal board 49 (Figs. 1 and 2) and the other portion 47 being provided to act as an anchor for one end of a centering spring 51 (Figs. 1, 2, and 3).

Again referring to Figs. 1, 2 and 3, it will be seen that the pivot shaft 11 of the armature 9 is provided with soft rubber sleeves 53 and 55 and is clamped between the groove supporting surfaces 27 and 35 of the unitary pole piece structure and the bottom plate, respectively. These two members are clamped together by means of two screws 57 and 59 which extend into the tapped holes 31 and 29, respectively, of the pole piece structure.

The rubber sleeves 53 and 55 are provided mainly to reduce friction, but they also act to damp the armature and to center it in the air gap to a certain extent.

An electric pick-up coil 61 in the form of a flat torus is positioned inside the U-shaped pole piece structure and surrounding the armature 9. It will be understood that the coil 61 is slipped into position before the armature 9 is placed in position in the air gap 23.

The pick-up coil 61 is centered with respect to the armature 9 and held in that position by means of a bushing 63 of insulating material which fits tightly in the opening 25 and slightly above the armature pivot shaft 11 at one end and against the inside of the pole pieces at the other end.

The armature is centered by means of the centering spring 51 which has a sharp bend therein, one end of the spring being soldered or otherwise fastened to one end of the armature pivot shaft 11, as by extending through an opening therein. The other end of the spring 51 is positioned between the bottom plate portion 47 and a rectangular washer 65 whereby it may be clamped in position, after the armature has been centered, by tightening a screw 67. In practice, the spring 51 is made long enough so that it can be held easily for centering the armature. After the armature is centered, the spring is clamped in position and the extra length of spring cut off. It will be noted that the centering spring acts in bending rather than in torsion.

In assembling the pick-up unit the terminal board 49 is fastened to the upwardly extending portion 45 of the bottom plate by means of a screw 72 (Fig. 2). The permanent magnet 7 is then placed with its pole faces on top of the pole pieces 13 and 15 and the assembled unit 5 and the permanent magnet 7 are placed inside the casing 3. The bottom plate 32 is fastened to the front side of the casing 3 by means of screws 69 which engage the holes 41. This clamps the magnet 7 between the pole pieces and two projecting elements 71 at the top of the casing 3.

The ends of the pick-up coil 61 are next connected to the two conductors 73 of a shielded cable 75 which leads to a suitable amplifier (not shown).

The pickup-arm 1 is supported from a suitable base member 77, a pivot arm 79, and a hollow pin 81. The pivot arm 79 consists of a horizontal section 83 and a vertical section 85, the horizontal section being pivotally fastened to the sides of the pick-up arm 1 by means of a horizontal pin 87 extending through the horizontal section 83 and the said sides. The vertical section 85 has a vertical hole therein, this section being positioned above the base member 77 and held in pivotal relation thereto by means of the pin 81 which is flared out at the bottom. A set-screw 89 holds the pivot arm 79, the pin 81, and the base member 77 in assembled relation.

A washer 99 is located between the pivot arm 79 and base member 77, the washer having a lug 101 which extends between lugs 103 on the base member 77 (as shown in Fig. 7) for limiting the swing of the pick-up arm 1. A bifurcated lug 105 extends upwardly from the washer 99 to engage the set-screw 89 whereby washer 99 is caused to rotate with the pick-up arm 1.

The preferred method of making the unitary pole piece structure is as follows: A flat plate of magnetic material is cut to the desired size and bent into the form of a U. Portions are then removed from the upper side of the bent plate by means of a circular cutting tool to form a comparatively narrow bridge of material in the middle of this side.

The upper side is then formed into two pole pieces separated by an air gap by sawing through the narrow bridge of material. At the same time, a cut is made in the lower side of the bent plate for preventing the short-circuited turn effect.

Next, the bent plate is turned over and an opening drilled opposite the air gap. Also, the two threaded holes are made on opposite sides of the opening. The groove for the armature pivot shaft is then cut in the plate directly opposite the two cuts made by the saw.

It will be noted that the groove is cut so deep that the plate is thin at the bottom of the groove whereby the flux leakage through the metal bridging the magnet poles is kept at a minimum value. It will also be noted that the cut made at the back of the U by the circular tool is not deep enough to cut entirely through the curved section joining the flat sides of the U. Thus, the section indicated at 107 (Fig. 2), together with the thin plate section at the bottom of the groove, joins the two end portions of the U-shaped unit and holds them in fixed and rigid relationship.

In addition to the previously mentioned advantages of my unitary pole piece construction there is the advantage that the air gap is always uniform since it is sawed or milled out with reference to the semi-circular groove. Another advantage is that the two upper faces of the pole pieces are always exactly in the same plane whereby they make good contact with the pole faces of the permanent magnet to keep the reluctance of the magnetic circuit at a minimum.

Various modifications may be made in my invention without departing from the spirit and scope thereof, and I desire, therefore, that only such limitations shall be placed thereon as are necessitated by the prior art and set forth in the appended claims.

I claim as my invention:

1. In a pick-up unit, a supporting member, a

5 pair of pole pieces positioned above said member and having an air gap therebetween, said pole pieces being integral with said supporting member, and a permanent magnet positioned with its pole faces above said pole pieces and having its pole faces directly in contact therewith.

2. In a pick-up unit, a supporting member having a groove cut transversely thereof, a pair of pole pieces attached to said member and positioned above it, said pole pieces having an air gap therebetween which is opposite said groove, a magnet for said pole pieces, a shaft having an armature mounted thereon substantially at right angles thereto, said armature being positioned 10 in said air gap and said shaft being positioned in said groove, and means for holding said shaft in position in said groove.

15 3. A pick-up unit according to claim 2 characterized in that said pole pieces are integral with 20 said supporting member.

4. A pick-up unit according to claim 2 characterized in that said groove is on the under side of said supporting member, and further characterized in that said armature extends through 25 an opening in said member and into said air gap.

5. In a pick-up unit, a supporting member, a pair of pole pieces attached to said member and positioned above it, said pole pieces having an air gap therebetween, a magnet for said pole pieces, 30 a shaft, an armature mounted thereon substantially at right angles thereto, said armature being

positioned in said air gap and said shaft being positioned below said member, and means including a bottom plate for clamping said shaft against said member, said bottom plate forming a portion of a casing for said pick-up unit.

5

6. A unitary pole piece structure for a permanent magnet in an electrical pick-up, said structure comprising a bottom plate and a pair of pole pieces positioned above and spaced away from said bottom plate, said pole pieces and said bottom plate being an integral unit.

10

7. A unitary pole piece structure for an electrical pick-up, said structure comprising a bottom plate, a pair of pole pieces positioned above and spaced away from said bottom plate, the ends 15 of said pole pieces being separated by an air gap, a connecting section extending from one edge of said bottom plate to a side of one pole piece, and a second connecting section extending from said one edge to a side of the other pole piece.

20

8. In an electrical pick-up including a field-magnet, a vibratory armature having an active end and a stylus carrying end, a translating coil for said armature, an integral pole piece structure for said magnet having portions thereof providing a fixed and nonadjustable air gap for the active armature end, and another portion of said pole piece structure having an opening therein through which the stylus end of said armature extends.
